HIGH-FREQUENCY ELECTRON TUBE AND
CIRCUITPaul Haas, New Hyde Park, N. Y., assignor to
Sylvania Electric Products Inc., a corporation
of Massachusetts

Application March 13, 1948, Serial No. 14,726

1 Claim. (Cl. 250—36)

1 This invention relates to electron-discharge tubes and, more generally, to electron-discharge tubes combined in high-frequency circuits.

Bypass structures are often required for maintaining a pair of electrodes connected in a high-frequency circuit at different direct-current potentials without however interrupting the high-frequency circuit. Tubes of the so-called planar-grid type are often used in high-frequency circuits in which the annular terminal of one electrode is connected to one wall of a bypass structure that surrounds the terminal. Tubes and tube-circuit combinations of this kind are subjected to severe impact in special applications.

An object of the present invention is to improve bypass constructions used in combination with electron-discharge tubes of the planar-grid type, for making the combination simpler, more effective, and easier to assemble.

A further object is to improve electron-discharge devices in respect to their ability to withstand extreme impact stresses.

According to one phase of this invention, the envelope of a planar grid tube is formed in part of a hollow metallic extension of the planar grid terminal. This terminal can be connected in the high-frequency circuit, and in this combination the extension can be utilized as one wall of a bypass structure. That terminal and extension also act as a function to resist acute endwise acceleration stresses applied by a non-metallic wall or envelope-portion that carries another electrode. As a further feature the metal portion of the envelope is tapered, somewhat as a cone, for firm seating of the envelope in its circuit assembly and for imparting excellent shock resistance to the tube-and-circuit combination. Furthermore, by properly proportioning the metal envelope wall, the bypass can be made to assume the dimensions necessary to serve also as one wall of a coaxial quarter-wave line having an open termination. In the circuit assembly, this results in injecting a minimum of impedance where the triode joins the high-frequency circuit. This is a feature disclosed but not claimed in copending application Serial No. 14,807, filed March 13, 1948, by George D. O'Neill.

Further objects and features of novelty will be apparent from the following detailed description of an illustrative embodiment of the several features of this invention, from which the foregoing objects and features of novelty will be more fully understood and appreciated. The single figure in the accompanying drawing is a longitudinal cross-sectional view of an illustrative tube and high-frequency circuit combination.

2 In the drawing, circuit assembly 10 includes multiple components threaded together to enclose and firmly support a triode 12. This circuit and tube combination, used for illustrative purposes, forms a dynatron oscillator more fully described in copending application Serial No. 631,454, filed July 5, 1946, by George D. O'Neill. In this dynatron oscillator a high-frequency oscillation is set up between positive grid 14 and dynode or secondary-emitting anode 16, which oscillation is utilized to excite resonator 18 for yielding energy to load coupling device 20. The triode also includes a cathode 22 for supplying the electron stream for grid 14 and dynode 16. A pair of leads are provided for heating the filamentary cathode, only one 24 of which is shown, and a third lead 26 for flashing the getter, and for direct-current connection to the positive grid. Dynode 16 is carried by a rod 28 which is sealed in a glass portion 30 forming a wall of the triode envelope that insulates dynode 16 and positive grid 14 apart. Glass wall 30 is enclosed in the high-frequency field set up in cavity 18 without adverse effect. Planar grid 14 is supported in a threaded ring 32 and is thus adjustably carried by annular terminal 34 of the planar grid to which glass wall 30 is sealed hermetically. For coupling positive grid 14 into the high-frequency circuit including resonator 18, without short-circuiting the positive grid to the dynode in respect to direct current, a bypass construction generally designated 36 is provided including an insulating sleeve 38. Ring 32, annular terminal 34 and rod 28 are inactive in respect to the generation of the oscillations, but they constitute active portions of the high-frequency circuit and in effect constitute parts of a coaxial resonator including cavity 18. The bypass surrounds terminal 34 at the point where that terminal is to join the remainder of resonator 18, so that only a loop or edge portion 58 of the bypass divides the external resonator 18 and annular terminal 34.

Bypass 36 here assumes the form of a quarter-wave concentric or coaxial transmission line having an open termination. Sleeve 40 forming a structural part of resonator 18 serves as one wall of the bypass 36. The other wall 42 of the bypass is also the lower side-wall of the evacuated envelope. Walls 40 and 42 of the bypass are extended to open termination 44 of the open quarter-wave transmission line by the upper end of composite tube 50, 52, 54 and by bottom metal wall 48 of the triode, and dielectric sleeve 38 is extended by dielectric ring 46. Metal envelope portions 48 and 42 are welded together at their edges to form a flange 56 that is clamped within dielectric

members 38 and 46 when tube 50 is tightened into sleeve 40. The external diameter of envelope portion 42 and the internal diameter of sleeve 40 decrease with increasing distance from tube 50, so that when tube 50 is tightened into sleeve 43 the metal envelope becomes firmly clamped and seated. Dielectric sleeve 38 is of sufficiently yielding nature to accommodate slight irregularities either in envelope portion 42 or sleeve 40, and slight eccentricities of the envelope and the sleeve.

The impedance of open-termination 44 desirably is infinite, so as to be transformed at the input gap 58 to zero impedance. However there is the possibility of coupling between resonator 18 and the exterior at the open-termination 44, and to decrease this coupling (which may cause losses and instability) a series-connected pair of short-circuited lines 60 and 62 is arranged in series with gap 44. The result is to produce very nearly ideal zero-impedance conditions at gap 58. Cavities, or more properly coaxial lines 60 and 62 are provided by properly shaping the nested tubes 50, 52 and 54. This features is disclosed and claimed in copending application Serial No. 14,807 of George D. O'Neill.

When cathode 22, dynode 16 and positive grid 14 are connected to different potential points of more or less critical values in a direct-current power supply such that dynode 16 is lower in potential than grid 14 but positive in relation to the cathode, and dynode 16 and positive grid 14 are connected to resonator 18, oscillations will be generated in the triode as more fully described in the above-cited application Serial No. 681,454 of George D. O'Neill. Energy from the dynode oscillator can then be abstracted at load coupling 20.

A high-frequency circuit formed by dynode rod 28 and the walls of resonator 18 as extended by terminal 34 and threaded ring 32 is divided ad-

jacent terminal 34 by direct-current insulating material without serious effect on that high-frequency circuit. The glass wall of the evacuated envelope enters the high-frequency field of the resonator without serious adverse effect, and is well supported on the metal envelope wall that serves also as a shielding enclosure for the dynatron cathode structure, as a firm mechanical seat for the triode in the circuit assembly and as one wall of the bypass.

Detailed variations of the foregoing novel features as well as applications of the features separately in other combinations will occur to those skilled in the art, wherefore I desire the appended claim to be accorded broad interpretation consistent with the spirit and scope of the invention.

What is claimed is:

High frequency apparatus having an electron discharge tube including a pair of mutually insulated electrodes and a generally conical metallic envelope portion extending from one of said electrodes and substantially enclosing the other of said pair of electrodes, a resonator coupled to said one electrode, said resonator having a generally conical seat receiving said metallic envelope portion and being spaced therefrom by a cushioning layer of dielectric material, and means firmly retaining said metallic envelope portion and said seat in assembled relation.
